(57) **CLAIM**

The ornamental design for a beverage dispenser, as shown and described.

DESCRIPTION

FIG. 1 is a front view of a beverage dispenser, showing our new design.

FIG. 2 is a rear view of the beverage dispenser of FIG. 1. FIG. 3 is a top view of the beverage dispenser of FIG. 1. FIG. 4 is a bottom view of the beverage dispenser of FIG. 1.

FIG. 5 is a left side view of the beverage dispenser of FIG. 1.

FIG. 6 is a front left view of the beverage dispenser of FIG. 1.

FIG. 7 is a top left view of the beverage dispenser of FIG. 1.

FIG. 8 is a top left perspective view of the beverage dispenser of FIG. 1.

FIG. 9 is a rear left top perspective view of the beverage dispenser of FIG. 1.

FIG. 10 is a right side view of the beverage dispenser of FIG. 1.

FIG. 11 is a right front perspective view of the beverage dispenser of FIG. 1.

FIG. 12 is a top right view of the beverage dispenser of FIG. 1.

FIG. 13 front right top perspective view of the beverage dispenser of FIG. 1; and,

FIG. 14 a rear right top perspective view of the beverage dispenser of FIG. 1.

The beverage containers to be used in the beverage dispenser are shown in broken lines and form no part of the claimed design. The remaining broken lines in the Figures show portions of the beverage dispenser and form no part of the claimed design.

1 Claim, 14 Drawing Sheets
